(57) **CLAIM**

The ornamental design for the vehicle diagnostic tablet, as shown and described.

DESCRIPTION

FIG. 1 is a front perspective view of the first embodiment of the vehicle diagnostic tablet shown with a pivoting rear support stand in an extended orientation;

FIG. 2 is a front plan view of the vehicle diagnostic tablet of FIG. 1;

FIG. 3 is a rear plan view of the vehicle diagnostic tablet of FIG. 1 shown with the pivoting support stand in a retracted orientation;

FIG. 4 is a left side edge elevation view of the vehicle diagnostic tablet of FIG. 1 shown with the pivoting support stand in a retracted orientation;

FIG. 5 is a right side edge elevation view of the vehicle diagnostic tablet of FIG. 1 shown with the pivoting support stand in a retracted orientation;

FIG. 6 is a top side edge elevation view of the vehicle diagnostic tablet of FIG. 1 shown with the pivoting support stand in a retracted orientation;

FIG. 7 is a bottom side edge elevation view of the vehicle diagnostic tablet of FIG. 1 shown with the pivoting support stand in a retracted orientation;

FIG. 8 is a front perspective view of a second embodiment of the vehicle diagnostic tablet;

FIG. 9 is a front plan view of the vehicle diagnostic tablet of FIG. 8;

FIG. 10 is a rear plan view of the vehicle diagnostic tablet of FIG. 8;

FIG. 11 is a left side edge elevation view of the vehicle diagnostic tablet of FIG. 8;

FIG. 12 is a right side edge elevation view of the vehicle diagnostic tablet of FIG. 8;

FIG. 13 is a top side edge elevation view of the vehicle diagnostic tablet of FIG. 8; and,

(Continued)

FIG. 14 is a bottom side edge elevation view of the vehicle diagnostic tablet of FIG. 8.

The broken lines in the drawings are for the purpose of illustrating portions of the vehicle diagnostic tablet that form no part of the claimed design.

1 Claim, 10 Drawing Sheets
